UNITED STATES PATENT OFFICE

ROBERT A. PONSELLE, OF NEW YORK, N. Y.

SANDING MACHINE

Application filed June 28, 1927. Serial No. 202,021.

This invention relates to so-called sanding machines used for wood working purposes and is concerned more particularly with an abrasive tool or element used in such a machine to perform the actual work. This tool is mounted on the machine to be rotated at a suitable rate of speed and has an abrasive surface which contacts with the article to be operated on.

10 The tools employed in machines of the kind referred to ordinarily include a support which is operatively connected to a driven shaft, and the abrasive surface takes the form of a disc of abrasive sheet material removable secured to the support. As these discs become worn and lose their abrasive qualities in service, more or less frequent replacement is required, depending on the character of the material being worked, and the 20 operation being performed.

The object of the present invention is to provide a sanding machine which includes a readily removable abrasive tool, this tool being so arranged and constructed that replacement of the worn abrasive disc is easily and rapidly accomplished. The new tool further includes a reliable clamping means for holding the disc in position while the tool is in use and also a locking device for locking the 30 clamping means against releasing the disc during use. This locking device is brought into action and is effective only when the tool is mounted in operative position in the machine, and accordingly, it in no way interferes with the release of the clamping means under those conditions that would prevail when such release is intentional and replacement of a disc is to be made. So long as the 35 tool is in operative position, however, the clamping means is locked and the disc is held firmly so that tearing or other injury to it is avoided.

The new tool is of especial utility in a portable sanding machine to be used for treating wood floors and that adaptation of

the invention will be described merely for purposes of illustration. In one such machine the tool or element is mounted on the end of a vertical driven shaft, and the face of the tool covered with the abrasive disc lies in contact with the floor, the entire weight of the machine pressing the cutting surface against the floor.

The construction of a sanding machine for treating floors is illustrated in the accompanying drawings, in which,

Fig. 1 is a view of a convenient form of the sanding machine in side elevation with certain parts shown in vertical section on the line 1—1 of Fig. 2,

Fig. 2 is a transverse sectional view on the line 2—2 of Fig. 3,

Fig. 3 is a view in side elevation showing the driving connections and the tool detached from the remainder of the machine,

Fig. 4 is a transverse section on the line 4—4 of Fig. 1,

Fig. 5 is a vertical section on the line 5—5 of Fig. 4,

Fig. 6 is a sectional view of a detail, and

Fig. 7 is a face view of the abrasive disc.

While the present tool is suitable for use with various types of machines to be used for different purposes, it is here illustrated in the form most suitable for use in a sanding machine for operating on floors. This machine includes a base or frame 10 on which is mounted an electric motor 11 having a driving shaft 12 which drives a chain 13 through suitable gearing and a vertical shaft mounted within a housing 14. The chain drives a sprocket wheel 15 mounted on the upper end of a tubular hub 16 which is in turn mounted on upper and lower ball bearing assemblies 17, 18, on a stud shaft 19 extending through a boss 20 in the frame and having a nut 21 at its upper threaded end 22 by which the stud shaft is held in position. The ball bearing assemblies are mounted in position with a driving fit and are held separated by a tu-

tular spacer 23. A cap plate 24, held in place by screws on the lower end of the stud shaft, assists in holding the inner race of the lower assembly 18 in position, and a cap 25 mounted on the lower end of the hub 16 by screws, serves to close the end of the hub and also supports the outer race of the lower bearing assembly. A ring plate 26 secured to the upper face of the sprocket wheel overlies the upper end of the tubular hub so as to prevent the entrance of dirt into the interior of the hub.

Mounted on the lower face of the sprocket wheel around the hub is a ring 27 which is provided with a plurality of spaced depending lugs 28, each of which carries a plate 29 on its lower end, these plates lying in a plane parallel to the lower face of the sprocket wheel. Each plate is held in position by screws 30 which extend through the lug and the sprocket wheel and also serve to hold the ring 27 in place on the sprocket wheel. The plates 29 project beyond the lugs in the direction in which the sprocket wheel is to be driven.

The tool includes a support 31 provided with a flat disc 32 at one end and on its opposite face the support has a tubular extension 33 forming a recess 34. On the upper end of the extension is a ring 35, having tangential arms 36 corresponding in number to the number of lugs 28. Each of the arms has an under-cut portion, and the arrangement of the arms is such that the tubular extension 33 of the support may be passed over the end of the shaft and by a turning movement of the support the plates 29 on the lugs 28 may be engaged in the under-cut recesses in the arms. The support may thus be mounted on the lugs of the ring 27 carried by the sprocket wheel 15 and a driving connection between the sprocket wheel and the support is thus established. When the support is to be removed from the end of the shaft, the support is given a slight turning movement, freeing the arms from the plates 29, whereupon the support may be removed from the shaft endwise.

The support has a central depression 37 having a sloping side wall, and a ring 38 of yielding material, such as felt, is secured to the lower face of the plate 32. Secured in the support is a threaded stud 39, held in position in any convenient manner and projecting downwardly into the depression, as shown in Fig. 1.

The abrasive material 40 is in the form of a circular disc of slightly greater diameter than the diameter of the felt ring 38. The abrasive disc has a central hole 41 and a plurality of slits 42 are cut radially in the disc, as illustrated in Fig. 7. The circle drawn through the outer ends of the slits is of substantially the same diameter as the inner diameter of the ring of felt, and when the

abrasive disc is placed on the face of the felt the tabs 43 defined by the slits are bent inwardly so as to lie against the sloping wall of the depression 37. These tabs are clamped in position against this wall by a clamping device consisting of a ring 44 having a side wall of the same slope as the slope of the wall of the depression. A circular plate 45 has a channel 46 in its edge in which is received the inner edge of the ring 44, and plate 47 secured to the face of the plate 45 slightly overlies the portion of the ring 44 received in the channel 46. The ring 44 and the plate 45 are thus secured together against detachment but are capable of relative movement. The plate 45 has a central hub 48 threaded on the end of the stud 39 and wing lugs 49 are formed on the lower face of the plate, these lugs providing means for turning the plate on the stud.

The upper face of the plate 45 is provided with a circular row of locking teeth 50 and mounted in a boss 51 in the support 31 is a pawl 52. This pawl has its lower end cut at an angle, as shown at 53, (Fig. 5) and it carries a pin 54 entering a notch in the lower end of the boss 51, the pin preventing the pawl from turning. A leaf spring 55 is secured to the upper end of the pawl by means of a portion of the pawl which passes through a hole in the spring and is upset to form a rivet head. The spring 55 has a portion which extends inwardly toward the upper end of the stud 39 and this spring tends to hold the pawl retracted into the boss 51.

When the tool is to be put in operation, a disc of abrasive paper of the proper size is provided, the central hole is cut in it, and it is then slit radially, as shown in Fig. 7. The support, with the felt layer in position, is then turned up-side-down, the abrasive disc is put in place, and the tabs are bent downwardly so as to lie against the sloping wall of the depression in the support. The plate 45 with ring 44 secured to it, is now threaded on the stud 39 and turned until the sloping face of the plate is brought into engagement with the tabs of the abrasive disc. The plate is turned until the face of the ring clamps these tabs tightly between the face of the ring and the sloping wall of the depression in the support. The support is now placed on the end of the driving shaft of the machine and turned until the arms carried by the support are engaged by the lugs on the ring carried by the sprocket. If no locking means for the clamping device were provided, the rotation of the support accompanied by the jarring to which the machine is subjected in use, would cause the clamping device to become loose and the abrasive disc would slip and stand still so that it would do no useful work.

and might become injured by the rotation of the support.

With the present tool, however, the placing of the support with the disc in place on the end of the shaft brings the spring 55 into contact with the end plate 25 on the hollow hub of the sprocket, and the spring is bent downwardly, forcing the pawl 52 into locking engagement with one of the 10 teeth on the plate 45. The plate 45 is thus prevented from turning, and the tabs on the abrasive disc are securely clamped throughout the period of use of the machine. The spring is shaped so that if, when the support is mounted on the end of the hub of the 15 sprocket wheel, the end cap projects downwardly to a greater extent than is necessary to force the pawl into locking engagement with the teeth, the spring is simply flexed 20 to a greater extent without disturbing the engagement of the pawl and teeth.

As soon as the support is removed from the end of the shaft, the spring is free to return to its normal position, and it retracts the pawl from engagement with the teeth. The plate 45 may now be turned by the wing lugs, releasing the clamping ring from engagement with the tabs of the abrasive disc, and the disc may be removed and 30 another one easily put in position. It will be observed that the ring 44 and the plate 45 are capable of relative movement of rotation, but are otherwise secured together against detachment. This permits the 35 clamping ring to be forced tightly into clamping engagement with the tabs of the abrasive disc, although the ring 44 does not turn. Consequently the tabs are not subjected to a tearing action. At the same time 40 the clamping ring and plate are secured together so that there is no likelihood that the ring will be lost.

The new tool has been shown arranged for use on a machine suitable for treating floors, this machine having a carriage provided with wheels 56 which may be swung downward into engagement with the floor to permit the machine to be moved over the floor while the abrasive tool is clear of the latter. The machine is also provided with the usual handle 57, to which the motor leads are secured, and the usual switch for the control of the motor is also mounted on the handle. The tool is adapted for other 55 uses than with a floor machine, as will be readily apparent.

I claim:

1. In a sanding machine, the combination of a driven shaft, a support removably mounted at the end of the shaft, an abrasive disc on the support, means for securing the abrasive disc in position on the support, and means carried by the support for locking the securing means in effective position, the 60 said locking means engaging the shaft when

the support is mounted thereon and being rendered effective thereby.

2. In a sanding machine, the combination of a driven shaft, a support removably mounted at the end of the shaft, an abrasive disc on the support, a clamping disc for holding the abrasive disc on the support, and a locking device carried by the support and engaged by the shaft when the support is mounted thereon, the device being rendered 70 effective thereby to lock the clamping disc in clamping position.

3. In a sanding machine, the combination of a driven shaft, a support removably mounted at the end of the shaft, an abrasive disc on the support, a clamping disc for holding the abrasive disc on the support, this clamping disc being provided with locking teeth, and a locking device carried by the support and engaged by the shaft when 80 the support is mounted thereon, the device being forced thereby into locking engagement with the teeth on the clamping disc.

4. In a sanding machine, the combination of a driven shaft, a support removably mounted at the end of the shaft, an abrasive disc on the support, a clamping disc for holding the abrasive disc on the support, this clamping disc being provided with locking teeth, and a spring-pressed pawl carried by 90 the support and forced by engagement with the shaft when the support is placed thereon into locking engagement with the teeth on the clamping disc.

5. In a sanding machine, the combination of a driven shaft, a support removably mounted at the end of the shaft and having a recess into which the end of the shaft projects, an abrasive disc carried by the support, a clamping disc for holding the abrasive disc 100 on the support, locking teeth on the clamping disc, and a spring-pressed pawl mounted on the support and forced by the spring into the said recess, this pawl being so arranged that it is forced out of the recess 105 into engagement with the said locking teeth by engagement with the end of the shaft when the support is placed thereon.

6. In a sanding machine, the combination of a driven shaft, a support removably mounted at the end of the shaft and having a recess into which the end of the shaft projects, an abrasive disc carried by the support, a clamping disc arranged to clamp the central portion of the abrasive disc against the 110 support, locking teeth on the clamping disc, a pawl on the support movable to engage the said locking teeth and thereby effective to prevent the clamping disc from releasing the abrasive disc, and a spring on the support tending to hold the pawl out of engagement with the teeth, this spring being engaged by the shaft when the support is placed thereon, and flexed to force the pawl 115 into engagement with the teeth.

7. In a sanding machine, the combination of a driven shaft, a support mounted on the shaft, an abrasive element, means for holding the abrasive element on the support, and cooperating locking elements on the support and on the holding means, said elements being brought into locking engagement only when the support is mounted on the shaft.

5 10 In testimony whereof I affix my signature.
ROBERT A. PONSELLE.
